UNITED STATES PATENT OFFICE.

JAMES HUMPHREY, OF TORONTO, CANADA, ASSIGNOR OF ONE-HALF TO
WILLIAM K. GEORGE, OF TORONTO, CANADA.

APPARATUS FOR SHAPING HOLLOW METAL WARE.

SPECIFICATION forming part of Letters Patent No. 772,940, dated October 25, 1904.

Application filed December 6, 1902. Serial No. 134,192. (No model.)

To all whom it may concern:

Be it known that I, JAMES HUMPHREY, of the city of Toronto, in the county of York, Province of Ontario, Canada, have invented 5 certain new and useful Improvements in Apparatus for Shaping Hollow Metal Ware, of which the following is a specification.

The object of my invention is to devise means for rapidly fluting, embossing, or otherwise shaping hollow metal ware by means of water under pressure. I am aware that it is not broadly new to employ water for this purpose; and my invention consists, essentially, in the means employed to close the die while 15 the water is being displaced to force the metal blank into the pattern of the die and in the means for holding the die and removing the finished article, substantially as hereinafter more specifically described and definitely 20 claimed.

Figure 1 is a sectional elevation of my improved apparatus and its operating mechanism. Fig. 2 is a sectional plan view showing the plunger and die-cover. Fig. 3 is a vertical section showing a modification of the die and cover. Fig. 4 is a plan view of a divided die. Fig. 5 is a vertical section of another modification of my apparatus. Fig. 6 is a front elevation of the apparatus.

30 In the drawings like letters of reference indicate corresponding parts in the different figures.

In Fig. 1 I show my apparatus with its operating mechanism, the latter being shown 35 in a more or less conventional form. In this view A is the bed of the press, and B the framework of the guides for the reciprocating parts. Suitably secured to the bed A is the die-holder C, within which is placed the 40 removable die D. As dies of different depths will be used at different times, I prefer to place a plate E in the bottom of the die-holder, which may be removed when a deeper die is to be employed. By this arrangement I save a 45 considerable amount of metal in the construction of shallow dies. Just at the upper edge of the die a laterally-extending shoulder a is formed in the die-holder surrounded by the annular flange b. F is a cover suitably shaped

at its lower side to fit within the annular 50 flange b. Its lower surface may be shaped to engage the shoulder a; but I prefer to employ the construction illustrated in Fig. 1, in which an annular plate G is interposed between the bottom of the cover and the shoulder. This plate is held in position by the bolts c passing through holes in the cover, these holes being counterbored to provide shoulders for engagement by the heads of the bolts to limit the vertical play of the annular plate. A flange d is formed around the outer edge of this plate adapted to engage the under side of the packing-ring H, placed in a suitable recess around the lower portion of the cover F. From this construction it 60 follows that if the cover be pressed down to bring the plate G in engagement with the shoulder a the packing-ring will be compressed and consequently closely extended 65 against the inner side of the flange b, making 70 an absolutely water-tight joint. Through the center of the cover works the plunger I, adapted to descend within the die. A suitable stuffing-box or gland J is provided about the plunger to give a water-tight joint between 75 it and the cover.

Although I have described the die-holder and die as being separate, yet it will be readily seen that they might be made integral with one another without altering the essential features of the invention. When the apparatus is in use, the die and die-holder practically form the die and will be so described in the claims.

I may say that the form of the apparatus 85 just described is that best adapted for dishes—that is, dies used in forming comparatively flat open dishes.

The operation of the apparatus is substantially as follows: The die is heated, preferably to a temperature of 200° or 300° Fahrenheit, either by being warmed before being placed in the die-holder or in any other suitable manner. The die itself, it will be understood, is fluted or embossed or otherwise shaped to correspond with the pattern to be given the finished article. A metal blank K, pressed or spun so as to approxi-

mate to the general shape of the die, is then placed in position. This blank has preferably a flange formed thereon extending over the substantially horizontal upper portion of the die illustrated or preferably into the shoulder α . A quantity of hot water is now poured into the blank, and the cover F is then brought down by suitable mechanism, such as herein-after described, to effectually close the die, as already described. At the same time the pressure of the plate G on its flanged upper edge holds the latter so tightly in contact with the die and die-holder that the water cannot get underneath it to pass between the metal of the blank and the die. When the cover is firmly down in position, the plunger descends and displaces the water within the blank, forcing the metal of the latter into all the flutings, embossing, or other peculiarities of the shaping of the die. It will of course be understood that the stroke of the plunger or the quantity of water displaced by the plunger is just sufficient to force the metal of the blank to assume the contour of the die. I deem it preferable, however, to provide a relief-valve to allow of the escape of surplus water to prevent the pressure becoming so excessive as to break any portion of the apparatus. I preferably locate this relief-valve L in the side of the plunger I and form a passage-way e through the plunger communicating with the relief-valve. Any excess of pressure is thus safely taken care of. The great pressure exerted in all directions when the plunger descends into the water naturally has a tendency to spring up the cover, and leakage might occur were it not for the plate G and the rubber packing-ring. The pressure of the water on the plate compresses the packing and maintains a tight joint, and the greater the pressure the greater the compression and the tighter the joint even if the cover be sprung up slightly from its seat.

While any operating mechanism which will bring the cover F down to close the die and subsequently project the plunger within the die will answer the purpose of my invention, yet in Fig. 1 I illustrate conventionally one method of performing these operations. M is a holder shaped as a sleeve surrounding the plunger I. To this holder the die-cover F is suitably secured. The holder M is vertically movable on the guides f or in any other way common in press construction. To the upper end of the plunger is pivoted one end of the pitman N, the other end being connected to the crank O, fast on the shaft P, journaled in the frame B. Q represents toggle-levers pivoted together and having their lower ends pivoted on lugs g on the holder M and their upper ends on studs h on the frame of the machine. One of these toggle-levers alone is shown in the drawings. The upper half of each toggle-lever is slotted or grooved, as indicated, for engagement by a pin i , secured

to the upper end of the plunger. This slot is so shaped that while the pin is passing up or down the upper end of it the holder is being rapidly raised or lowered, and while the pin is passing up or down the portion of it which is vertical in the drawings a "dwell" occurs, during which the cover is held firmly in contact with the die through the three pivots of the toggle-levers being in line with one another. When this occurs, it will be seen that the holding down of the cover is entirely independent of the motion of the plunger, the strain being directly from the holder to the frame of the machine, the pin i having merely the function of preventing the pivots getting out of line until it again engages the upper portions of the slots in the toggle-levers.

Other constructions may be devised which will answer the purpose of my invention, the important feature being the mechanical reciprocation of the cover and the plunger and the independent downward movement of the latter after the die has been closed.

I am aware that it is not broadly new to form hollow metal ware by displacing the water in a closed die; but I am not aware that any one has heretofore provided such means for closing the die and operating the parts as I have just described. The great advantages are rapidity of action and the certainty and ease of manipulation. When the apparatus is in operation, I am not troubled with any leakage of water which would necessarily mar the perfection of the shape of the blank, as any water which improperly escapes means a failure in forcing some part of the blank into intimate contact with the die.

In Fig. 3 I show a slight modification in which the die and holder are adapted for the formation of a tall narrow article. In this case a much smaller plunger is used, and the laterally-extending shoulder α slopes somewhat downward. The annular plate G is shaped so as to press the upper edge of the metal blank against this shoulder in just the same manner as in the formation shown in Figs. 1 and 2. It will be noticed that the cover fits around the upper end of the die. This is an important feature of my invention as applied to dies for construction of tall comparatively slender articles or dies which, owing to the shape of the article, are necessarily divided vertically into several parts to permit of the removal of the finished article. (See Figs. 3 and 4.) The divisions may extend from top to bottom of the die, or the bottom may be formed of a single separate piece. (See Fig. 3.)

With a divided die used for articles formed with a flaring mouth, as shown in Fig. 3, the pressure of the annular plate G tends to spread the parts of the die at their upper ends, so that spaces will be formed into which the internal pressure will force the metal of the blank, causing nasty ridges; but the upper

end of the parts of the die are tapered externally, as shown in this figure, and the cover correspondingly shaped to embrace them. The pressure from within is perfectly resisted by the pressure from without and the parts of the die are firmly held in their proper position. I do not illustrate in this figure the packing-ring H, which is shown in Fig. 1 as combined with the annular plate G to compress said ring; but this construction may be employed, if desired, though its most useful purpose is with comparatively flat shallow dies, such as shown in Fig. 1. In Fig. 1 the die-holder is shown bolted to the bed of the press. The arrangement shown in Fig. 3 is more suitable for long-necked articles. In this figure I show a plate T, bolted to the bed of the press. The bottom of the die, it will be noticed, comes flush with the bottom of the die-holder, and a projecting pin j is formed on the bottom of the die extending into a similarly-shaped hole in the plate T. When this projection is engaged with the hole, the die is properly centered beneath the cover and plunger. When the cover and plunger are up, the die-holder may be lifted by means of the handles k. Then by striking the pin j on some solid object the die will be forced up out of the holder and may be taken apart and the finished article removed. This projecting of a portion of the die below the level of the bottom of the die-holder is an exceedingly useful feature of my invention, and a modification is exemplified in Fig. 5 which will be most extensively employed with sectional dies. In this form the bottom S' of the die, with the projection j, is separate from the rest of the die, and when the die-holder and die are removed the bottom remains on the plate T. In order to have some portion of the die to bring into contact with some solid object, the sides U of the die project below the bottom of the die-holder, which latter is shouldered and flanged, as shown, to engage the similarly-shaped upper surface of the plate T. This construction of the plate and die-holder causes the die to be held accurately centered below the cover and plunger, while the bottom S' of the die is always held centered by its projection j fitting the hole in the plate T. With this construction the die-holder and die are as readily removed as with the form shown in Fig. 3 and the die subsequently extracted for the removal of the finished article. In this form the upper portion of the die is engaged by the cover in the same manner as shown in Fig. 3, as dies of this shape are necessarily made in several vertical pieces. I also show in this figure a packing-ring H between the annular plate G and the bottom of the cover. There is a modification in the details of this arrangement, however, as the flange d is formed on the bottom of the cover and the recess for the packing in the plate G. The plate G is held by bolts c in the same manner as in Fig. 1;

but the bottom of the cover is formed of a separate plate V, held in place by screws l. This construction is necessitated owing to the location of the bolts c.

In Fig. 1 in order to lift the die after the pressing of the article to permit of the removal of the latter I show an ordinary die-lifting apparatus commonly used in draw-presses instead of the arrangement shown in Figs. 3 and 5. This consists of a vertical lifting-rod R, operating through suitable apertures in the bed and die-holder and having connections S and S' with the holder M. When the holder rises after the pressing of an article, the lifting-rod R comes in contact with the bottom of the die or the plate E and lifts the die up to a position in which it is readily accessible for the removal of the finished article. I do not claim this, however, as my invention.

What I claim as my invention is—

1. In apparatus for shaping hollow metal ware, a die provided with a flange surrounding a laterally-extending shoulder; a cover; an annular plate held at the under side of the cover so as to have a slight vertical motion and adapted to engage the shoulder and fitting within the flange; and a ring of packing located between the plate and cover, in combination with a reciprocating plunger working through the cover and adapted to enter the die; means for causing the cover to descend to force the annular plate into contact with the aforesaid shoulder; and means for subsequently projecting the plunger into the die, substantially as described.

2. In apparatus for shaping hollow metal ware, the combination of a die; a mechanically-reciprocated cover adapted to close the die and engage the edge of a blank placed therein and a mechanically-reciprocated plunger working through the cover adapted to enter the die, substantially as described.

3. In apparatus for shaping hollow metal ware the combination of a die; a mechanically-reciprocated cover adapted to close the die and engage the edge of a blank placed therein; a mechanically-reciprocated plunger working through the cover adapted to enter the die; and a relief-valve communicating through the plunger with the interior of the die when the latter is closed, substantially as described.

4. In apparatus for shaping hollow metal ware, the combination of a die-holder; a die fitted within the die-holder and having a portion projecting below the lower side of the die-holder; and a plate adapted to support and removably engage the projecting part of the die, in combination with a cover adapted to close the die; a plunger working through the cover and adapted to enter the die; means for reciprocating the cover; and means for reciprocating the plunger, substantially as described.

5. In apparatus for shaping hollow metal ware, the combination of a die-holder; a die fitted within the die-holder and having a portion projecting below the lower side of the die-holder; and a plate adapted to support and removably engage the projecting part of the die and die-holder, in combination with a cover adapted to close the die; a plunger working through the cover and adapted to enter the die; means for reciprocating the cover; and means for reciprocating the plunger, substantially as described.

6. In apparatus for shaping hollow metal ware, the combination of a die-holder; a vertically-divided open-mouthed die fitted within the die-holder and projecting above the upper edge of the same, in combination with a cover fitting about the upper part of the die and having a portion fitting within the open mouth of the same; a plunger working through the cover and adapted to enter the die; means for reciprocating the cover; and means for re-

ciprocating the plunger, substantially as described.

7. In apparatus for shaping hollow metal ware, the combination of a die-holder; a vertically-divided open-mouthed die fitted within the die-holder and having its upper portion inwardly beveled and projecting above the edge of the same; in combination with a cover having a beveled recess formed therein adapted to engage the similarly-beveled outer surface of the upper part of the die and having a portion fitting closely within the open mouth of the die; a plunger working through the cover and adapted to enter the die; means for reciprocating the cover; and means for reciprocating the plunger, substantially as described.

Toronto, November 28, 1902.

JAMES HUMPHREY.

In presence of—

J. EDW. MAYBEE,
JOHN G. RIDOUT.
